UNITED STATES PATENT OFFICE.

DAVID E. ROSS, OF LA FAYETTE, INDIANA, ASSIGNOR TO ROSS GEAR AND TOOL COMPANY, OF LA FAYETTE, INDIANA, A CORPORATION OF INDIANA.

STEERING-GEAR.

1,136,556.

Specification of Letters Patent. Patented Apr. 20, 1915.

Application filed March 31, 1913. Serial No. 757,937.

To all whom it may concern:

Be it known that I, DAVID E. Ross, of La Fayette, in the county of Tippecanoe and State of Indiana, have invented certain new and useful Improvements in Steering-Gear; and I hereby declare that the following is a full, clear, and exact description thereof, reference being had to the accompanying drawings, which form part of this specification.

This invention is a novel improvement in steering-gear for automobiles, motor boats and the like, and is particularly designed for use with electric vehicles which ordinarily employ a lever for operating the steering shaft instead of a wheel.

The object of the invention is to provide a steering gear which can be readily operated by such a lever without any liability or possibility of reverse pressure on the ball-arm or steering-crank, improperly shifting the steering shaft or lever.

The invention provides novel means whereby the rocker shaft and steering-crank can be positively and easily rocked in either direction, and will be always absolutely locked against casual or back pressure movements in any and all positions to which it is adjusted, thus making the invention especially adaptable for electric automobiles and other vehicles intended to be operated by women.

I will explain the invention with reference to the accompanying drawings, which illustrate one practical embodiment thereof, although those skilled in the art might embody the invention in other forms after the invention is disclosed to them.

In the claims following the description are summarized the essentials of the invention and the novel features of construction and combinations of parts for which protection is desired.

In the drawings: Figure 1 is a plan view of the steering devices of a steering gear with the housing broken away to show the operative parts more clearly. Fig. 2 is a transverse section on line 2—2 of Fig. 1. Fig. 3 is a similar view on line 3—3 of Fig. 1.

In said drawings 1 represents the rocker shaft which is journaled in a bearing formed in a tubular extension 9^a of the casing 9, which may be of any suitable construction and incloses the main operative parts of the

steering heads and supports the rocker shaft and the steering shaft.

To the outer end of the rocker shaft 1 is connected the steering crank, or ball arm, 1^a; that may be of any suitable construction, 60 and is connected in the usual or preferred way, by means not shown, to the front-wheel supports of the vehicle. On the inner end of the shaft 1 is fixed a double armed lever 2 to whose arms are pivotally connected shoes 3 and 3^a, which are shown as pivoted on studs 2^a on the arms of the lever, at equi-distant points from the axis of the rocker shaft 1. The shoes 3, 3^a are adapted to respectively engage opposed cam surfaces 70 4^x and 5^x on slidable cam members 4 and 5, which are movable transversely of the shaft 1 and beside the lever 2. The cam members 4 and 5 lie parallel and are movable in opposite directions, simultaneously and equally, 75 so that while contact is maintained between the shoes and the cam-surfaces, the shaft 1 will be rocked in one direction or the other according to the movement of the cam members 4 and 5. Thus if cam members 5 be projected or moved to the right, Fig. 1, the shaft 1 will be rocked clockwise; while cam 4 is simultaneously retracted. If cam 4 be projected or moved to the right, cam 5 would be retracted, and the rocker shaft 1^a will 80 be moved anti-clockwise. In either case the cams and shoes always remain in contact and have an interlocking action when at rest, which prevents any back pressure on the rocker shaft 1 shifting the cams or shoes, 85 which lock in any position to which they are adjusted unless and until the cams 4 and 5 are purposely moved to shift the shoes. This interlocking action relieves the driver 90 of the shocks and jars on the vehicle wheels and obviates the possibility of the steering arm being wrenching from the driver's hand under extreme conditions of back pressure on the steering crank.

The cam surfaces 4^x, 5^x and the opposed faces of the shoes 3 and 3^a are generated on such curves that the shoes always remain in close contact with the cam surfaces in whatever direction the shaft 1 is rocked by the shifting of the cams 4 and 5. Equal travel on the part of the cam surfaces, causes equal movements of the two arms of the lever 1^a, and the angular travel of the rocker shaft per unit of longitudinal travel of the cams remains constant. The curves of the 105 110

cam surfaces may be so generated however that a minimum of angular travel of the rocker shaft is produced at the central parts of the cam surfaces and a maximum of 5 travel toward the extremes of the cam surfaces. As a result of this construction, although shaft 1 may be rocked either to right or left by shifting the cams 4 and 5 endwise; cams 4 and 5 cannot be shifted by any 10 reverse or back pressure applied to the outer end of the shaft 1, or the steering crank 1^a; and the vehicle wheels will be securely held in any position to which they have been adjusted by the steering gear, until shifted by 15 the operator.

As shown, the cams 4 and 5 lie substantially at right angles to the steering shaft 6, which is journaled in the casing in any suitable way, and this steering shaft is provided on its lower end with a T-head 6^a, which is preferably slotted on its under side, and in the example shown the shank of the cam 4 which extends to and beneath this T-head is provided with a hole in which is 20 fitted a pin or lug 4^a having a square head 4^b, which is slidably fitted in the slot in the adjacent arm of the T-head 6^a on the steering shaft. The cam 5 is similarly provided with a hole in which is a pin 5^a having a 25 head 5^b engaging the slot in the adjacent end of the T-head 6^a. The construction is such that if the steering shaft 6 is turned in one direction cam 4 will be projected and cam 5 retracted; and if the shaft 6 is turned 30 in the other direction, cam 5 will be projected and cam 4 retracted.

The shanks of the cams 4 and 5 carrying the studs 4^a, 5^a may be guided in a lateral extension 9^c of the housing 9 as shown and 40 the shaft 6 may be suitably journaled in an extension 9ⁿ of the housing, or in bearings attached thereto, in any desired manner. When attached to a vehicle the steering shaft will extend to the desired position adjacent 45 the driver's seat, while the steering crank 1^a will be in proper position for connection with the steering wheels of the vehicle.

It is desirable to always maintain close 50 sliding contact between the cam surfaces 4^x and 5^x and the respective shoes 3 and 3^a and to compensate for any wear thereon. As shown in the drawings I accomplish this by means of two oppositely tapered wedge 55 plates 7 and 7^a which are fitted together and arranged between the adjacent straight edges of the cams 4 and 5. The wedge 7^a may be fixed at one end to the end wall of the extension 9^c of the casing as indicated at 60 7^b. While the opposite end of the wedge 7 may be fitted in a socket 9^d in the wall of the casing, and can be locked in such socket by means of a screw 9^e, and can be adjusted longitudinally by a screw 9^f, as indicated in 65 Fig. 1. By adjusting wedge 7 longitudi-

nally of the wedge 7^a the cams can be separated more or less and any wear on the faces of the cams and shoes can be compensated for by so adjusting the wedges. The cam surfaces may be so generated that the shoes 70 on the arms would contact therewith at all times although the shoes were not located exactly equi-distant from the axis of the rocker shaft; in such case the cams would be similar and in proportion but not exact 75 duplicates, and the opposed shoes would be correspondingly varied; but in operation the shoes would always remain in contact with the opposed cam surfaces.

What I claim is:

1. In a steering gear, a member to be operated, devices connected with said member at points equi-distant therefrom, opposite cam members engaging said devices, a steering shaft, and a cross head connected therewith 85 and engaging the cam members and adapted to cause opposite movements thereof.

2. In a steering gear, the combination of a rocker-shaft, opposite shoes connected therewith at equi-distant points, opposite cam members engaging the respective shoes; a steering shaft, and a cross head thereon engaging said cam members and adapted to move them simultaneously and equally in 90 opposite directions.

3. In a steering gear, the combination of a rocker-shaft, opposite shoes connected therewith, an independent cam member engaging each shoe, said cam members being faced in opposite directions; a steering shaft, and a 100 cross head thereon engaging said cam members to move same equally and simultaneously in opposite directions.

4. In a steering gear, the combination of a rocker-shaft, opposite shoes connected therewith, a cam member engaging each shoe, said cam members being faced in opposite directions, a steering shaft, a cross head thereon for simultaneously operating said cam members, and means for adjusting the 110 cam members laterally.

5. In a steering gear, the combination of a rocker-shaft, opposite shoes connected therewith, an independent cam member engaging each shoe, said cam members being faced in 115 opposite directions; a steering shaft, a cross head thereon for simultaneously operating said cam members, and wedges extending axially of and between the cam members for adjusting them laterally.

6. In a steering gear, the combination of a rocker-shaft, opposite shoes connected therewith and equi-distant therefrom, oppositely facing longitudinally movable cam members engaging said shoes, a steering shaft, a head thereon, and a pin and slot connection between said head and each cam member.

7. In a steering gear, the combination of a rocker-shaft, opposite shoes connected therewith, oppositely facing longitudinally mov-

able cam members engaging said shoes, a steering shaft, a head thereon, a connection between said head and each cam member, and adjusting means interposed between the 5 cam members and connected to the housing of the steering gear, substantially as described.

8. In a steering gear, the combination of a 10 rocker-shaft, a double armed lever on said shaft, shoes pivotally connected to the arms of said lever, oppositely facing cam members engaging said shoes, a steering shaft, a double armed head thereon; connections between said head and said cams for simultaneously moving said cams to effect the 15 rocking of the shaft and the locking thereof in adjusted position, substantially as described.

9. In a steering gear, the combination of a 20 rocker-shaft, a double armed lever on said

shaft, shoes pivotally connected to the arms of said lever, oppositely facing cams engaging said shoes, a steering shaft, a double armed head thereon; and pin and slot connections between said head and said cams, 25 means for simultaneously moving said cams in opposite directions to effect the rocking of the shaft and the locking thereof in adjusted position, and adjusting means interposed between the cam members and connected to the housing of the steering gear, 30 substantially as described.

In testimony that I claim the foregoing as my own, I affix my signature in presence of two witnesses.
